UNITED STATES PATENT OFFICE.

DAVID F. VAUGHAN, OF HADDONFIELD, NEW JERSEY.

GUARD-RAIL FASTENER.

SPECIFICATION forming part of Letters Patent No. 775,738, dated November 22, 1904.

Application filed August 20, 1904. Serial No. 221,473. (No model.)

To all whom it may concern:

Be it known that I, DAVID F. VAUGHAN, a citizen of the United States, residing at Haddonfield, in the county of Camden and State of New Jersey, have invented certain new and useful Improvements in Guard-Rail Fasteners, of which the following is a full, clear, and exact description, reference being had to the accompanying drawings, of which—

- 10 Figure 1 is a plan view of my improved guard-rail fastener as in use. Fig. 2 is a section on line *xx*, Fig. 1. Fig. 3 is a plan of the fastener-plate detached. Fig. 4 is a plan of the brace detached.
- 15 This invention relates more particularly to the type of guard-rail fasteners shown and described in Letters Patent of the United States No. 564,350, granted to me July 21, 1896; and the object of the present invention is to render the construction and operation of such fastener more perfect.

20 The precise nature of the improvement will clearly appear from the following description, in connection with the drawings, in which the same reference-letters are used to denote the same parts as are used in my said patent.

25 C is the fastener-plate, upon which rests when the device is in use the main rail A and the guard-rail B, said plate and rails being secured to the tie by means of spikes *e*, *e'*, and *f*.

30 *h* is a brace-lug (hereinafter termed the "brace") which is fastened to the plate C by means of rivets *g*, and its inner side is adapted to fit and abut against the side of the head, the web, and the foot of the guard-rail, as shown.

35 In carrying out my improvement I provide the plate C with openings *c* and the brace *h* with lateral base extensions *h'* and forwardly-projecting lugs *h* on its lower side. In securing the brace to the plate C the lugs *h* are passed into the openings *c*, and when the brace is applied to the guard-rail B the lower forward ends of said lugs *h* extend under the foot of the rail, and the extensions *h'* will rest upon the top of said foot, and spikes *e* are driven through openings *h* in the brace and

openings *c* in the plate C, the heads of the spikes bearing upon the top of the extensions *h'*, as seen in Fig. 2.

50 While I prefer to make the outer wall of the opening F for the spike *e* inclined and stepped, as shown in my said patent, such construction is not essential.

55 It will be seen that as the foot of the rail extends between the projecting end of the lugs *h* and the end portion of the brace the rail B will be held against tilting outwardly when stress is exerted in that direction against the side of the rail by the wheels of a train of cars. Preferably the length of the lugs *h* is the same or a little less than that of the openings *c* in the plate, and thus the ends of the lugs abutting against the end wall of said openings serve to distribute the strain upon the spikes holding the fastener to the tie.

60 I remark that the side extensions *h'* of the brace may sometimes be dispensed with. In such case the heads of the spikes *e* would rest directly upon the foot of the guard-rail. I further remark that I would sometimes provide the plate C with the slot *k* for the passage 65 of the spike *k* for the main rail A, as in my aforementioned patent.

Having thus described my invention, I claim 70 as new and desire to secure by Letters Patent—

75 The guard-rail fastener comprising the plate upon which the guard and main rails are adapted to rest, and the brace secured to said plate, and whose inner end is adapted to fit against the side of the head, web, and upper side of the foot of the guard-rail, and having the forwardly-extending lugs entered in slots in said plate, and adapted to underlie the foot of the rail, substantially as and for the purpose set forth.

80 In testimony whereof I have hereunto affixed my signature this 18th day of August, A. D. 1904.

DAVID F. VAUGHAN.
